(57) **CLAIM**

The ornamental design for a wind chime electric hook, as shown and described.

DESCRIPTION

FIG. 1 is a first perspective view of a wind chime electric hook showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the wind chime electric hook in which the design is embodied that form no part of the claimed design.
